UNITED STATES PATENT OFFICE.

SUTTON STRONG, OF INDIANAPOLIS, INDIANA, ASSIGNOR TO O. E. KING & COMPANY, OF INDIANAPOLIS, INDIANA, A COPARTNERSHIP.

COPYIST'S LINE-GUIDE.

1,253,905.

Specification of Letters Patent. Patented Jan. 15, 1918.

Application filed September 14, 1916, Serial No. 120,079. Renewed August 13, 1917. Serial No. 186,064.

To all whom it may concern:

Be it known that I, SUTTON STRONG, a citizen of the United States, residing at Indianapolis, in the county of Marion and State of Indiana, have invented certain new and useful Improvements in Copyists' Line-Guides; and I do declare the following to be a full, clear, and exact description of the invention, such as will enable others skilled in the art to which it appertains to make and use the same.

My invention relates to improvements in line guides used by typewriter operators, bookkeepers, and others doing copying work requiring an efficient guide which may be moved downwardly along the sheet being duplicated as the lines thereof are copied.

The object of the invention is to simplify devices of the class set forth without destroying any of the advantages thereof, and to this end the improvements reside in the simple construction and arrangement of parts which will be hereinafter fully described and claimed, the descriptive matter being supplemented by the accompanying drawings which constitute a part of this specification and in which,

Figure 1 is a top plan view of the improved device showing one manner of mounting the same;

Fig. 2 is a longitudinal section of the form shown in Fig. 1;

Fig. 3 is an end elevation thereof;

Fig. 4 is a top plan view similar to Fig. 1 but showing this type of the invention mounted on a bookkeeper's copy holder;

Fig. 5 is an edge view of Fig. 4;

Fig. 6 is a face view of another type of copy holder equipped with the invention;

Fig. 7 is an edge view of Fig. 6; and

Fig. 8 is a plan view of a special type of indicator which may be used when copying figures.

Throughout the several views, the numeral 1 designates a one-piece tube having feet 2 at its ends, said tube being provided with a longitudinal slot 3 terminating a suitable distance from one of its ends and opening 50 through the other end of said tube.

A slide sleeve 4 surrounds the tube 1 and carries an internal guide 5 in which the operating rod 6 is received, said rod passing through the tube 1 and through the sleeve as shown clearly in Fig. 2. The rear end of the

rod has thereon a stop collar 7 to abut a stop 8 struck upwardly from the rear end of the tube in order to limit the rearward movement of said rod, forward movement thereof being controlled by a thumb nut 8' threaded 60 on the projecting rear end of said rod for contact with the rear end of the tube 1.

The front end of the rod 6 is directed upwardly and pivoted to a hand operated lever 9 whose upper end is provided with 65 a finger piece 10, the lower end of said lever being passed loosely through a slot 11 in the bottom of the tube 1 and held rockably in this position by means of upper and lower pins 12 and 13 passed through said lever 70 above and below the bottom of the tube. A spring 14 is coiled around the upper pin 12, one end of said spring bearing against the lever 9 while the other end thereof contacts with the bottom of the tube, said spring 75 serving to return the rod 6 to its initial position each time it is moved forwardly by operation of the lever 9. This lever is preferably channel-shaped as shown and the spring is received in the channel thereof. 80

The top of the sleeve 4 is formed with a slot 15 and in advance of said slot with an upstanding stop 16, and a gripping bar 17 passes into the sleeve through said slot with its upper end in contact with the stop. The 85 lower end of the gripping bar is formed with an opening 18 which receives the rod 6, and a coiled spring 19 is interposed between said end and the guide 5 whereby the bar 17 is normally canted to cause it to 90 travel forwardly with the rod 6 when the lever 10 is operated. When the rod moves in the other direction, however, it will slide freely through the opening 18 and will thus leave the slide 4 in its adjusted position. 95 For returning the slide to the rear end of the tube 1, the action of the spring 19 on the gripping bar 17 may be overcome by forcing forwardly on the projecting upper end of said bar. 100

A pair of clamping plates 20 are superimposed to one side of the sleeve 4 and are provided with opposed claws 21 which take over and under the tube 1 in contact with the ends of sleeve 4. Bolts having thumb nuts 22 pass through the plates 20 for drawing them toward each other and for forcing the claws 21 into frictional contact with the tube 1, whereby this friction will serve 105 to hold the sleeve 4 in the numerous posi- 110

tions to which it is adjusted by actuation of the lever 9. An indicating arm 23 may be secured at its inner end between the plates 20 as shown in most figures of the drawings, or a slotted indicator 23^a as depicted in Fig. 8 may be secured between said plates according to the style of work to be performed.

In Figs. 1, 2 and 3, the rear end of the tube 1 is shown provided with feet 2 as is likewise the front end thereof. In this type of the invention the front feet will rest on the work being copied as depicted in Fig. 2 in which the device is shown in use upon a book B. The rear feet 2 are adjustably secured by screws, bolts or the like 24 to the horizontal flange of an angular metal bar 25, the ends of the vertical flange of this bar being bent rearwardly and provided 20 with threaded studs 26 having thereon thumb nuts 27, said studs passing through vertical slots 28 in sheet metal posts 29 which are adapted to be secured to the top of a desk or table, as indicated in Figs. 25 1 to 3.

The post 29 may also be secured to a rectangular copy holding frame 30 which is disclosed in Figs. 4 and 5, said frame being hinged at its lower end to a suitable base 31 as indicated at 32, a swinging support 33 and a rack bar 34 being provided for holding the frame 30 at any suitable incline. The parts 30 to 34 simply illustrate a common type of copy holder used primarily by bookkeepers, and this device is merely shown for the purpose of disclosing the manner in which the improved device may be applied to such a copy holder.

In Figs. 6 and 7 another type of copy holder is shown to disclose yet another application of the invention. In these figures 40 35 designates a plate hinged at 36 to a base 37 and held at any incline by means of a swinging support 38 having projecting studs 45 39 at its upper end for reception in openings 40 in the downturned edges 41 of the plate 35. A suitable rubber bound paper clamp 42 is mounted on the upper end of the plate 35 and along the left hand edge of said 50 plate the invention is disposed as shown, the front and rear feet 2 being riveted or otherwise secured to the plate 35 and to one downturned edge 41 thereof.

Regardless of the application of the invention it will be extremely simple and efficient, being capable of use in connection with lines spaced different distances, adjustments being made by means of the thumb nut 8 to allow the operating rod 6 60 to move only the proper amount for advancing the indicator 23 or 23^a in the necessary step by step manner.

The slots 28, studs 26, and thumb nuts 27 permit vertical adjustment of the bar 25 65 and the parts carried thereby, to compen-

sate for books or stacks of paper of different thicknesses, and said bar serves as a paper weight when in any position to hold the leaves or pages out flat. The feet 2 at the other end of the tube 1 also perform somewhat the same function and may, if desired, be elongated. Other important features are that the entire device may be swung upwardly to a vertical position around the studs 26 to permit turning of 70 pages, and the indicating arm may be swung upwardly to permit reading of the matter covered thereby, said arm being also capable of operation when shifted to either side of the tube, and in some instances two arms 80 such as 22 may be used at the same time on opposite sides of said tube.

In the drawings a number of specific details have been shown for illustrative purposes and in view of the extreme simplicity 85 and advantages of this construction it constitutes the preferred form of the device. It is to be understood, however, that within the scope of the invention as claimed, numerous changes may be made without sacrificing the principal advantages. 90

I claim:

1. A copyist's line indicator comprising a tube having a longitudinal slot extending approximately throughout its length, a 95 slide surrounding said tube for both sliding and turning movement thereon, an indicator carried by said slide, a rod within the tube, means for moving said rod forwardly and returning it to its initial position, and means 100 passing through the slot in the tube for connecting the slide with the rod upon forward movement of the latter.

2. A copyist's line indicator comprising a tube having a slot extending approximately 105 throughout its length, a slide mounted on said tube for moving an indicator, a rod within the tube, means for moving said rod forwardly and then returning it to its initial position, a gripping bar passing through the 110 slot of the tube and a slot in the slide, said bar having an opening through which the operating rod passes, a stop against which the projecting upper end of said gripping bar bears at its front side, and a spring bearing 115 against the rear side of said bar at the lower end thereof for normally canting said bar to cause it to grip the operating rod when the latter moves forwardly.

3. The combination with a guide member, 120 a slide mounted thereon, and means for moving said slide along said member; of a pair of clamping plates having upper and lower claws receiving therebetween the guide member and bearing against opposite ends 125 of the slide, means for drawing the two clamping plates together; and an indicator having its inner end secured between said clamping plates.

4. A copyist's indicator comprising a tube 130

having a slot extending approximately throughout its length, a slide surrounding said tube for both sliding and turning movements thereon, an indicator carried by said slide a rod extending through said tube, an operating lever extending through the slot in the tube at the front end of the latter and fulcrumed to said tube, the operating rod being pivoted to said lever, and means extending through the slot for connecting the slide with the operating rod upon forward movement of the latter.

5. A copyist's line indicator comprising a pair of rigid vertical standards spaced apart, 15 a horizontal bar extending between said standards and adapted to rest on one edge

of the pages being copied to serve as a paper weight, the ends of said bar being vertically adjustable on said standards, a guide member secured to and extending at right angles 20 from said bar, lateral feet on the free end of said guide member to rest on the other edge of the pages being copied, and a line indicator carried by said guide member.

In testimony whereof I have hereunto set 25 my hand in the presence of two subscribing witnesses.

SUTTON STRONG.
